UNITED STATES PATENT OFFICE.

WILLIAM L. STEWART, OF WORCESTER, MASSACHUSETTS.

LAMP.

Application filed March 16, 1921. Serial No. 452,716.

To all whom it may concern:

Be it known that I, WILLIAM L. STEWART, a citizen of the United States, residing at Worcester, in the county of Worcester and State of Massachusetts, have invented new and useful Improvements in Lamps, of which the following is a specification.

This invention relates to improvements in means for diffusing illumination and 10 more particularly relates to improvements in lamps.

One of the objects of my invention is to provide improved means for giving electric light as well as gas light by means of a 15 unitary structure wherein the desirable qualities of attractiveness, ornamental effect, mechanical efficiency and all around usefulness are attained.

Another object of my invention is to provide an electric lamp also having a gas 20 lamp fixture connected thereto so as to adapt the lamp interchangeably to give out illumination employing either gas or electricity, at any one time.

A still further object of my invention is 25 to provide novel improvements in lamp shade designs, to enhance the appearance and utility of the aforementioned lamp and to assist in a better distribution of the light 30 rays particularly upon a table thereby resulting in a better focus of light than is obtained from most lamps.

And it is another object of my invention 35 to provide novel means of securing a lamp shade in position upon the pedestal of a lamp which is characterized by the fact that no tools are necessary to secure the shade upon the lamp.

With the above and other objects in view 40 my invention consists in the combination, arrangement and details of construction disclosed in the drawings and specification and then more particularly pointed out in the appended claims.

In the drawings wherein similar reference 45 characters designate similar parts throughout the respective views,

Figure 1 is a side elevation of my invention including the glass shade,

Figure 2 is a side elevation without the 50 glass shade being mounted thereon,

Figure 3 is a bottom plan view of the lamp,

Figure 4 is a vertical, sectional view 55 through the lamp,

Figure 5 is a fragmental, sectional view through a modification of my invention,

Figure 6 is a top plan view of Figure 5,

Figure 7 is a cross section through the 60 pedestal shown in Figure 5,

Figure 8 is a fragmental, sectional, detailed view of a lamp shade,

Figure 9 is a vertical, sectional view 65 through the lamp taken at right angles to Figure 4,

Figure 10 is a top plan view of Figure 2,

Figure 11 is a bottom plan view of the lamp shade,

Figure 12 is a sectional, detailed view of 70 the lower edge of the lamp shade,

Figure 13 is a detailed view of a corner of the lamp shade,

Figure 14 is a detailed, sectional, fragmental view of another corner of the lamp shade,

Figure 15 is a fragmental, detailed view 75 of a shade supporting arm, and,

Figure 16 is a plan view of a part to be described.

In the drawings which are merely illustrative of my invention, 1 designates the base portion of the lamp which is also formed with a plurality of props 2 located at the corner of the base portion 1. The base portion is formed centrally with a through 80 channel or passage 3 at one end of which fits a connector element 4, and this passage 3

communicates with a vertical channel or passage formed longitudinally through a support or pedestal 6. The upper end of the 85 pedestal is enlarged as at 7 and this end of the pedestal is adapted to carry a collar or headed portion, which may be in the form of a separate block 8 resting upon the flat top surface of the support or pedestal 6.

The upper end of the passage 5 is provided 90 with divergent branches M and N which communicate with continuations of these branches O and P formed through block 8 as clearly shown in Figure 4 and in the 100

branches O and P project the tubular terminals 9 and 10 of the electric bulbs 11 and 12, which electric bulbs are thus oppositely inclined so as to converge towards the pedestal.

There is a gas pipe 28 extending through the upper end of the passage 5 and running lengthwise of this passage being bent around at 28^a so as to project laterally in the base 110 passage 3 and has connected thereto a nipple

7 to which is secured a flexible gas pipe X. The upper end of the gas pipe is threaded for the reception of a nut 13 which forms part of the stem 14 of the gas mantle fixture and it will also be noted that the nut 13 clamps down tight upon the block 12^a which is secured upon the top of the block 8. This nut or clamping coupling 13 may be screwed upon either pipe 28 or pipe section 18. Electric wires Y connected together carrying a plug 48 adapted to have an electrical interfit with the connector element 4 and the wires run through the base passage 3 upwardly through the pedestal passage 5 and are connected to the electrical bulbs 11 and 12. It will be understood that the electric bulbs carry the usual switch chains (not shown.)

In order to simplify the arrangement and construction of all the parts there is shown in Figure 5 a fixture in the nature of a main pipe, the upper portion of which is designated 18 and the lower portion 15 there being formed at diametrically opposite points 25 of this pipe the divergent arms 16 and 17. The upper portion of the pedestal or support 6^a as shown in Figure 5 is headed as at 21 to provide an integral collar disposed to take the place of the separate collar 8, 30 and this headed portion is formed with a socket 23 which flares outwardly of the head and the oppositely inclined pipe branches or arms 16 and 17 fit snugly in this socket while the lower end of the pipe 16 fits snugly in 35 the passage 5' while the upper portion 18 of the pipe projects above the head 21. The arms 16 and 17 serve to provide integral means on the upper portion 18 of the gas fixture to limit the downward movement of 40 this gas pipe in said pedestal. A plug 19 fits around the portion of the pipe 18 and contacts the head 21 and is secured in position by the fasteners 20 entering the holes 24 formed in the head 21. The mantle 14 45 is then operatively connected to the projecting terminal of the pipe portion 18.

It will thus be seen that by connecting the plug 48 to the switch element 4 an electrical circuit is closed to the lamp bulbs 11 and 12 50 causing the bulbs to flash and glow and if the flexible gas pipe X is connected up to the proper gas fixture and gas introduced in the pipe the gas will find its way up the pipe 28 or through pipe section 18 of the 55 three-way gas fixture as shown in Figure 5, to the mantle and thus gas may be used for illumination purposes as well as electricity.

In order to obtain a better dissemination of the light rays it is necessary to employ my 60 lamp shade which will now be described. In order to support the lamp shade removably on the pedestal, I provide a plurality of shade supporting arms 26, four of which are disclosed. Each of these arms consists 65 of a lug 29 formed at its inner end and a

substantially right angular lug formed at its outer end, as shown in Figure 15, each of the lugs 29 are provided with a headed pin 30 adapted to engage a key hole slot 33 formed in a plate 32 so that the head of this 70 pin will be accommodated in a socket 31 formed into the pedestal. The idea is to insert the head of the headed pins 30 into the wide end of the key hole slot 33 and then by pressing the lug inwardly the head will 75 be locked in the narrow portion of this key hole slot. The lugs 27 formed upon arms 26 are also formed with key hole slots similar to the slots 33 adapted to be presented against pins 49^a secured upon four 80 diagonal straps 30^a forming part of the lamp shade.

The lamp shade consists of an upper rectangular strip 40 and a lower, larger rectangular strip 25, the last named strip being 85 wider than the strip 40. A series of diagonal strips 34 extend between the rectangular strips 40 and 25 and have beveled abutting edges engaging the sides of the strip 25 as shown in Figure 14. I provide four trapezoidal shaped glass panels 37 substantially of similar shape extending upwardly from the edges of the strip 25 and the lateral edges engaging under the strips 34 which may be grooved out as shown in Figure 8 to snugly 95 receive these edges of the glass panels 37, the strips 39 extend parallel to the strips 34 on the inner side of the shade and are positioned as shown in Figure 8 so as to engage the glass panels 37 at the same time these two 100 strips being secured together by the fasteners 30^a shown in Figure 8. Angle irons 41 are secured to the corners of both of strips 25 and 40 and have angularly inclined arms arranged in alinement and secured to the 105 respectively upper and lower ends of the strips 38 (see Figure 14.) In this manner the glass panels 37 are secured in proper position all around the shade. I also mount four glass strips arranged in two sets, the 110 first set being designated 37^a and the other set at right angles to the first set being designated 46. These glass strips are intended to overlie the inner sides of the strip 25 and are held against downward displacement by 115 the fasteners or clips 45, (see Figure 12) secured to the sides of the strips 25. The corners of the sides of the strip 25 having a beveled edge fit and their inner intersecting portions are connected to angle irons 43 120 which thus stiffen these parts and bridging the opposing edges of the side of the angle irons 43 are gussets 44 which also form abutments for the right angular disposed glass strip 37^a and 46. The sides of the strip 25 125 will preferably be cut away to provide desirable filigrees so as to enable the light to show through the glass strips 37^a and 46 which overlie their inner sides. When the light is shining from the mantle 14 or the electric 130

bulbs 11 and 12 the inclining glass panels 37 will be found to scatter and diffuse the light rays to advantage in all directions and will also send the rays downwardly thereby rendering this lamp fit as a table lamp and as a combined gas and electric lamp. By disconnecting the plug 48 from the switch element 4 the electric light circuit may be interrupted.

10 What I desire to claim and secure by Letters Patent is:

1. A lamp consisting of a base having a horizontal passage therein, a wooden pedestal secured down upon said base and having a vertical passage communicating with the horizontal passage, a pipe passing upwardly through the pedestal passage and projecting thereabove and having a lower curved portion projecting through the horizontal passage of said base at one side of the pedestal, electric lamp sockets in the upper end of said pedestal diverging with respect to said pipe upwardly outside said pedestal, a gas mantle secured to the upper end of said pipe, a block surrounding the upper projecting end of said pipe and laying on top of said pedestal, a nut carried by said pipe adapted to clamp down said block, and electrically fed lamps connected to said divergent lamp sockets.
2. A gas lamp consisting of a wooden pedestal having a flat base portion, said pedestal having a vertical and horizontal passage, a pipe having its main length received in the vertical passage of the pedestal and having a lower angular portion projecting out through the horizontal passage of the pedestal, a nipple connected to the lower end of said pipe and having an enlargement of the base portion, a connector element secured in the base channel at a point opposite to said mentioned nipple, a flexible gas pipe connected to said nipple, an electric plug connected removably to said connector element, an electric lamp device connected to

the upper end of said pedestal and electrical connections leading from said connector element to said electric lamp device.

3. In a device as described, in combination, a pedestal, a gas pipe extending thru said pedestal so as to project above its top portion, integral means on said pipe imbedded in said pedestal and limiting the downward movement of said pipe in said pedestal, a block around said pipe engaging the top of said pedestal, a coupling engaging the outer end of said pipe and clamping said block down on said pedestal, a burner connected at its lower end to said coupling, and a mantle carried by said burner.

4. In a device as described, in combination, a base portion, a wooden pedestal having a lower part secured centrally to said base portion, said pedestal being formed with a central vertical bore and said pedestal having its upper portion cut away so as to communicate with said central bore adapted to provide oppositely inclined walls, lamp sockets projecting into said cut-away portion and engaging the inclined walls thereof, and a gas burner pipe projecting into the uppermost end of said central bore.

5. In combination, a flat support, said flat support being cut away at various points to produce depressions, said depressions having rabbets, plates countersunk in said rabbets having key-hole slots, and a series of lamp shade supporting arms having angular lugs carrying pins projecting into said key-hole slots of said plates, said pins having heads projecting into said depressions.

In witness whereof he has hereunto set his hand and affixed his seal this 5th day of February, 1921.

WILLIAM L. STEWART. [L. S.]
